CLAIM

The ornamental design for a “robot”, as shown and described.

DESCRIPTION

FIG. 1 is a front, right perspective view of a robot in accordance with our new design;

FIG. 2 is a front elevation view thereof;

FIG. 3 is a rear elevation view thereof;

FIG. 4 is top plan view thereof;

FIG. 5 is a bottom plan view thereof;

FIG. 6 is a right-side elevation view thereof;

FIG. 7 is a left-side elevation view thereof;

FIG. 8 is a right-side elevation view thereof, shown in an alternate position of use; and,

FIG. 9 is a sliced section view taken along line 9-9 in FIG.

6 with internal mechanisms omitted.

The broken lines shown in the drawings depict portions of the robot that form no part of the claimed design.
